(57) **CLAIM**

The ornamental design for a jar for packaging, as shown and as described.

DESCRIPTION

The patent or application file contains at least one drawing executed in color. Copies of this patent or patent application publication with color drawing(s) will be provided by the Office upon request and payment of the necessary fee.

FIG. 1 is a front right top perspective view of a jar for packaging, showing my new design;

FIG. 2 is a front elevational view thereof;

FIG. 3 is a rear elevational view thereof;

FIG. 4 is a right side view thereof, a left side view thereof being the same image as that of the right side view thereof;

FIG. 5 is a top plan view thereof;

FIG. 6 is an enlarged front elevational view of the cap of the jar for packaging, showing the texture of a surface of the cap; and,

FIG. 7 is a reference perspective view of the jar for packaging, wherein the cap is detached from the body of the jar for packaging.

The symbol, which consists of 2 bands and 4 rectangular shapes, is depicted in FIGS. 1, 5 and 7, and forms part of claimed design, is a registered trademark of ACRO INC.
